Primary Examiner — Freda S Nunn(74) *Attorney, Agent, or Firm* — Banner & Witcoff, Ltd.(57) **CLAIM**

The ornamental design for a computer, as shown and described.

DESCRIPTION

FIG. 1 is a front perspective view of a computer showing our new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is a bottom perspective view thereof.

The broken line showing of the various unshaded elements of the computer illustrates environmental structure and forms no part of the claimed design.

1 Claim, 8 Drawing Sheets(56)
